UNITED STATES PATENT OFFICE.

JOHN V. PILCHER AND JOHN F. BABBITT, OF LOUISVILLE, KENTUCKY; SAID BABBITT
ASSIGNOR TO SAID PILCHER.

SEPARABLE BUTTON.

Application filed August 13, 1923. Serial No. 657,092.

To all whom it may concern:

Be it known that we, JOHN V. PILCHER and JOHN F. BABBITT, citizens of the United States, and residents of Louisville, in the county of Jefferson and State of Kentucky, have invented certain new and useful Improvements in Separable Buttons, of which the following is a specification.

Our present invention relates to improvements in separable buttons and is shown and described herein as embodied in a separable link cuff button, though not limited to this specific use.

The invention aims to provide a button which can be economically manufactured, which will be strong and durable in use, and one in which the parts will be firmly and securely locked together while yet capable of being easily separated or uncoupled.

With these and other objects in view, the invention includes the novel features of construction and arrangement and combination of parts hereinafter described, and particularly defined by the appended claims.

An embodiment of our invention is illustrated in the accompanying drawings, in which:—

Figure 1 is a central vertical section through our improved button with the parts separated, the section being taken on line 1—1 of Fig. 2.

Fig. 2 is a section taken through the head on line 2—2 of Fig. 1.

Fig. 3 is a section on line 3—3 of Fig. 2, and

Fig. 4 is a section on line 4—4 of Fig. 2, looking in the direction of the arrow.

Figs. 5, 6 and 7 are views of a modified form.

Referring by reference characters to this drawing, the numeral 1 designates the stud member which may carry any desired form of flange (single or multiple) being shown as embodied in a multiple flange type, the upper flange 1^a being shown and the lower portion of the stud being broken away. The separable head or socket member, comprises a back piece or collet 2 having a tubular portion of hub 2^a and flange 2^b, the hub being of the proper shape and size to receive the stud 1. The outer edge of the collet is flanged or turned upwardly and the face member or cover 2^c of the button has

its edge spun or flanged down over the edge 55 of the collet in the customary manner.

Within the space thus formed is located a plate member 3 which has a flanged outer edge 3^a clamped between the back and cover member, and is provided with a central aperture in alignment with the bore of the hub. This plate serves as a support for the stud-engaging means, which consists of an approximately semicircular spring 4 (preferably slightly exceeding a semi-circle) fitting the seat formed by the flange 3^a and retained in position thereby, the spring having parallel end portions 4^a which are designed to engage the annular recess 1^b in the stud, this recess having its upper wall perpendicular to the axis of the stud so that when engaged by the spring the parts are positively locked together.

The plate member 3 has, at the edge of its central opening, upwardly turned flanges 3^b, which are provided with recesses b at their ends in which the parallel portions of the spring rest when the stud is not in position in the socket, these recesses b serving to prevent the spring portions 4^a from being deflected upwardly when the stud member is inserted, it being understood that the end of the stud member is rounded, or otherwise shaped to provide a substantially wedge-shaped end, or its equivalent, as indicated at 1^c, so that forcible entry of the stud member in the socket will force the spring arms 4^a apart until, on complete entry of the stud member, they snap into the recess 1^b.

Preferably the ends of the spring are formed of substantially S-shape, as shown.

With the spring ends or arms 4^a engaging the recess 1^b, it will be seen that the parts are securely locked together. To release the shank from the said arms, we provide wedging means which takes the form of a push piece 5 stamped from sheet metal and fitting a centrally arranged opening in the cover member 2^c. This push piece has depending wedge-shaped portions, or wings 5^a, lying between the spring ends 4^a on opposite sides of the stud, and just within the flanges 3^b, so that an inward push on the push piece 5 will cause the wedges to spread the spring ends 4^a and release the stud member.

The margins of the push piece between the wedges are bent outwardly, as indicated

at 5°, to form lugs or ears, underlying the cover to retain the push piece in position.

Instead of having the retaining or locking spring 4 located in the outer portion or head of the socket member, as shown in Figs. 1 to 4 inclusive, the base of the hub portion might be modified to receive it, as shown in Figs. 5, 6 and 7. In this form the hub member has its lower portion flared 10 outwardly as shown at 2^x and the base flange 2^y is united to it at its outer edge by a curved joint which leaves an intervening space in which the spring 4^x is located, the parallel portions of the spring indicated at 15 *x'* resting on shoulders *y* and bearing against lugs or ears *y'*. The push piece 5^x is, of course, correspondingly elongated.

Having thus described our invention, what we claim is:

20 1. A button of the separable type, having a recessed stud, a circular socket member to receive the stud, a spring catch comprising a semi-circular spring portion terminating in approximately parallel portions to engage 25 said stud, and a push piece having a wedge-shaped portion acting parallel to the axis of the stud and lying between said parallel portions.

2. A button of the separable type having 30 a recessed stud, a socket member to receive the stud, a spring catch comprising a spring compressible in a direction laterally of the socket member, a plate within the socket having a flange portion, said spring engaging 35 said flange portion.

3. A button of the separable type having a recessed stud, a socket member to receive the stud, a spring catch adapted to engage 40 the stud, a plate within the socket member, said spring engaging the plate, said plate preventing vertical movement in both directions of the spring.

4. A button of the separable type, having a recessed stud, a socket member to receive 45 the stud, comprising a shell cover and back secured together at their edges, a plate member having a margin confined between the edge portions of the shell and back, and

having a central opening and upwardly turned flanges adjacent the same with recessed ends, a spring overlying said plate member and having parallel stud engaging arms resting in said notched ends when no stud is held thereby, and a push piece having wedge-shaped portions lying between 55 said spring arms and spaced apart to admit the stud.

5. A button of the separable type having a recessed stud, a socket member to receive the stud, a spring adapted to engage the 60 stud and retain the same within the socket, and a push piece operating through an aperture in the top of the socket and adapted to free the stud from the spring catch, movement of the push piece toward the stud causing 65 compression of the spring.

6. A button of the separable type having a recessed stud, a socket member, to receive the stud, a plate within the socket member, a spring catch in proximity to said plate 70 and adapted to engage the stud, said plate having a central aperture through which the stud is adapted to pass, upwardly turned flanges adjacent the aperture with recessed ends, the ends of said spring catch engaging 75 the recessed ends of the upwardly turned flanges on the plate.

7. A button of the separable type having a recessed stud, a socket member to receive the stud, a spring catch adapted to engage 80 the stud and retain the same within the socket, and a plate within the socket supporting said spring catch.

8. A button of the separable type having a recessed stud, a socket member to receive 85 the stud, a spring catch adapted to engage the stud and retain the same within the socket, and a plate within the socket supporting said spring catch, said plate having an upset portion also engaging the spring, 90 which prevents upward movement of the spring.

In testimony whereof, we affix our signatures.

JOHN V. PILCHER.
JOHN F. BABBITT.
